UNITED STATES PATENT OFFICE.

HENRY SHELDEN GERMOND, JR., OF BAYONNE, NEW JERSEY, ASSIGNOR TO NEW YORK REVOLVING PORTABLE ELEVATOR COMPANY, OF JERSEY CITY, NEW JERSEY, A CORPORATION OF NEW JERSEY.

HOISTING MECHANISM.

1,277,712.

Specification of Letters Patent. Patented Sept. 3, 1918.

Application filed November 24, 1913. Serial No. 802,596.

To all whom it may concern:

Be it known that I, HENRY SHELDEN GERMOND, Jr., a citizen of the United States of America, residing at Bayonne, in the county of Hudson and State of New Jersey, have invented certain new and useful Improvements in Hoisting Mechanism, of which the following is a specification, reference being had to the accompanying drawings:

10 This invention relates to improvements in hoisting mechanism and particularly to improvements in hoisting mechanism in which a windlass is used; and an object of this invention is the provision in a hoisting mechanism of the character just set forth, of brake mechanism in which the operator will be safeguarded from injury due to the backward throw of the crank used in operating the hoisting mechanism. Other features of this invention will be pointed out in the description and claims which follow hereinafter.

15 mechanism of brake mechanism which shall be automatically controlled by the weight raised by the hoisting mechanism. Another object of this invention is the provision in a hoisting mechanism of the character just set forth, of brake mechanism in which the operator will be safeguarded from injury due to the backward throw of the crank used in operating the hoisting mechanism. Other features of this invention will be pointed out in the description and claims which follow hereinafter.

20 Figure 1 is a side elevation of a portable elevator or tiering machine embodying this invention; Fig. 2 is an elevation looking in the direction of the arrow A in Fig. 1; Fig. 3 is a detail showing in plan the lever mechanism by which the cable-supporting pulley transmits the weight of the load to the brake-mechanism; and Fig. 4 is a section on the line 4--4 of Fig. 1, showing on an enlarged scale the brake-band connections.

25 The truck *a* is supported upon the caster or steering-wheel *b* and two other wheels *c*. This truck *a* carries the base *d* from which rise the standards *e* comprising the vertical frame-members the tops of which are joined by the cross-beam *f*. Arranged to slide between the uprights or standards *e* is a load-carrying platform *g* to which is fastened one end of a cable *h* the other end of which is wound around the drum *i* of the hoisting mechanism. This drum *i* may be rotated by turning by means of the crank *j*, the winding-shaft *k* upon which are mounted fast the spur-gear *p* and the pinion *n*. Upon the drum-shaft *o* there is

30 mounted fast the spur-gear *p* which is in mesh with the pinion *n*. An inspection of Fig. 1 will show clearly how the cable *h* is wound upon the drum *i* by turning the winding-shaft *k* by means of the crank *j*. The spur-gear *m* upon the winding-shaft *k* meshes with the pinion *q* fast upon the brake-shaft *r*. Idly mounted upon the latter shaft is a brake-disk *s* formed in one

35 wall of which is formed the ratchet-teeth *u*. Upon the brake-shaft *r* there is keyed a pawl-carrier *v* which carries a spring-controlled pawl *w*. The brake-disk *s* is normally kept from turning on the brake-shaft *r* by means of a brake-band *x*.

40 Upon the cross-beam *f* there is mounted a bracket *y* in which is fulcrumed a lever *z* one end of which carries the pulley 2 over which passes the winding-cable *h*. The other end of the lever *z* is tied by the cable 3 to the brake-band-controlling lever 4 one end of which is bifurcated and is mounted fast upon the brake-releasing shaft 5 around which is looped one end of the brake-band *x* the other end of which is looped around the cross-pin 6 which is carried by the forked end of the brake-band-controlling lever 4.

45 Figure 1 is a side elevation of a portable elevator or tiering machine embodying this invention; Fig. 2 is an elevation looking in the direction of the arrow A in Fig. 1; Fig. 3 is a detail showing in plan the lever mechanism by which the cable-supporting pulley transmits the weight of the load to the brake-mechanism; and Fig. 4 is a section on the line 4--4 of Fig. 1, showing on an enlarged scale the brake-band connections.

50 The truck *a* is supported upon the caster or steering-wheel *b* and two other wheels *c*. This truck *a* carries the base *d* from which rise the standards *e* comprising the vertical frame-members the tops of which are joined by the cross-beam *f*. Arranged to slide between the uprights or standards *e* is a load-carrying platform *g* to which is fastened one end of a cable *h* the other end of which is wound around the drum *i* of the hoisting mechanism. This drum *i* may be rotated by turning by means of the crank *j*, the winding-shaft *k* upon which are mounted fast the spur-gear *p* and the pinion *n*. Upon the drum-shaft *o* there is

55 mounted fast the spur-gear *p* which is in mesh with the pinion *n*. An inspection of Fig. 1 will show clearly how the cable *h* is wound upon the drum *i* by turning the winding-shaft *k* by means of the crank *j*. The spur-gear *m* upon the winding-shaft *k* meshes with the pinion *q* fast upon the brake-shaft *r*. Idly mounted upon the latter shaft is a brake-disk *s* formed in one

60 wall of which is formed the ratchet-teeth *u*. Upon the brake-shaft *r* there is keyed a pawl-carrier *v* which carries a spring-controlled pawl *w*. The brake-disk *s* is normally kept from turning on the brake-shaft *r* by means of a brake-band *x*.

65 Upon the cross-beam *f* there is mounted a bracket *y* in which is fulcrumed a lever *z* one end of which carries the pulley 2 over which passes the winding-cable *h*. The other end of the lever *z* is tied by the cable 3 to the brake-band-controlling lever 4 one end of which is bifurcated and is mounted fast upon the brake-releasing shaft 5 around which is looped one end of the brake-band *x* the other end of which is looped around the cross-pin 6 which is carried by the forked end of the brake-band-controlling lever 4.

70 Figure 1 is a side elevation of a portable elevator or tiering machine embodying this invention; Fig. 2 is an elevation looking in the direction of the arrow A in Fig. 1; Fig. 3 is a detail showing in plan the lever mechanism by which the cable-supporting pulley transmits the weight of the load to the brake-mechanism; and Fig. 4 is a section on the line 4--4 of Fig. 1, showing on an enlarged scale the brake-band connections.

75 The truck *a* is supported upon the caster or steering-wheel *b* and two other wheels *c*. This truck *a* carries the base *d* from which rise the standards *e* comprising the vertical frame-members the tops of which are joined by the cross-beam *f*. Arranged to slide between the uprights or standards *e* is a load-carrying platform *g* to which is fastened one end of a cable *h* the other end of which is wound around the drum *i* of the hoisting mechanism. This drum *i* may be rotated by turning by means of the crank *j*, the winding-shaft *k* upon which are mounted fast the spur-gear *p* and the pinion *n*. Upon the drum-shaft *o* there is

80 mounted fast the spur-gear *p* which is in mesh with the pinion *n*. An inspection of Fig. 1 will show clearly how the cable *h* is wound upon the drum *i* by turning the winding-shaft *k* by means of the crank *j*. The spur-gear *m* upon the winding-shaft *k* meshes with the pinion *q* fast upon the brake-shaft *r*. Idly mounted upon the latter shaft is a brake-disk *s* formed in one

85 wall of which is formed the ratchet-teeth *u*. Upon the brake-shaft *r* there is keyed a pawl-carrier *v* which carries a spring-controlled pawl *w*. The brake-disk *s* is normally kept from turning on the brake-shaft *r* by means of a brake-band *x*.

90 Upon the cross-beam *f* there is mounted a bracket *y* in which is fulcrumed a lever *z* one end of which carries the pulley 2 over which passes the winding-cable *h*. The other end of the lever *z* is tied by the cable 3 to the brake-band-controlling lever 4 one end of which is bifurcated and is mounted fast upon the brake-releasing shaft 5 around which is looped one end of the brake-band *x* the other end of which is looped around the cross-pin 6 which is carried by the forked end of the brake-band-controlling lever 4.

95 Figure 1 is a side elevation of a portable elevator or tiering machine embodying this invention; Fig. 2 is an elevation looking in the direction of the arrow A in Fig. 1; Fig. 3 is a detail showing in plan the lever mechanism by which the cable-supporting pulley transmits the weight of the load to the brake-mechanism; and Fig. 4 is a section on the line 4--4 of Fig. 1, showing on an enlarged scale the brake-band connections.

100 The truck *a* is supported upon the caster or steering-wheel *b* and two other wheels *c*. This truck *a* carries the base *d* from which rise the standards *e* comprising the vertical frame-members the tops of which are joined by the cross-beam *f*. Arranged to slide between the uprights or standards *e* is a load-carrying platform *g* to which is fastened one end of a cable *h* the other end of which is wound around the drum *i* of the hoisting mechanism. This drum *i* may be rotated by turning by means of the crank *j*, the winding-shaft *k* upon which are mounted fast the spur-gear *p* and the pinion *n*. Upon the drum-shaft *o* there is

105 mounted fast the spur-gear *p* which is in mesh with the pinion *n*. An inspection of Fig. 1 will show clearly how the cable *h* is wound upon the drum *i* by turning the winding-shaft *k* by means of the crank *j*. The spur-gear *m* upon the winding-shaft *k* meshes with the pinion *q* fast upon the brake-shaft *r*. Idly mounted upon the latter shaft is a brake-disk *s* formed in one

110 wall of which is formed the ratchet-teeth *u*. Upon the brake-shaft *r* there is keyed a pawl-carrier *v* which carries a spring-controlled pawl *w*. The brake-disk *s* is normally kept from turning on the brake-shaft *r* by means of a brake-band *x*.

retrograde movement of the winding-shaft r can occur. When it is desired to release the brake-disk s , the workman is forced to remove his crank j from off the winding-shaft k (or the brake-shaft r , as the case may be) and place it upon the brake-releasing shaft 5. The workman next turns the latter shaft so as to swing the free end of the brake-band-controlling lever 4 downwardly against the tension produced in the tie-rope 3 by the weight of the platform g and its load. In this way the slight movement necessary to loosen the brake-band x is produced; and the brake-band being loosened, the brake-disk s , the pawl-carrier v and the brake-shaft r will rotate together in a retrograde or backward direction, thereby allowing the platform g and its load to descend. The control thus obtained is perfect and the lowering of the platform is made swift and certain; and, at the same time, the workman is safeguarded from injury due to the backward throw of the crank-handle j .

25 I claim:

1. A hoisting mechanism comprising load-supporting means; a brake mechanism; automatically-acting devices through which the weight of the load controls said brake mechanism; means for releasing said brake mechanism; and an operating device adapted to control alternatively both said means.

2. A hoisting mechanism comprising load-supporting means; windlass mechanism controlling the same; a brake for said mechanism; automatically-acting devices through which the weight of the load controls said brake; means for releasing said brake; and an operating member adapted to control alternatively said load-supporting means and brake-releasing means.

3. A hoisting mechanism comprising a load-supporting cable; a load-raising windlass mechanism upon which said cable is wound to raise the load and from which said cable is paid out to lower the load; a brake mechanism which while set permits said windlass to be freely operated to wind up said cable and raise the load but which prevents said cable from being paid out to lower the load; devices by which said cable and its load are supported and said brake mechanism is held in set position by the load during the raising thereof; and means by which said brake mechanism is in opposition to the weight of the load released from the action thereof and said windlass mechanism is freed to pay out said cable.

4. A hoisting mechanism comprising a load-supporting cable; a load-raising windlass mechanism upon which said cable is wound to raise the load and from which said cable is paid out to lower the load; a brake-

disk idly mounted on said windlass mechanism; a brake-strap for said brake-disk; means by which said windlass mechanism is interlocked with said brake-disk; devices by which said cable and its load are supported and said brake-strap is held in set position by the load during the raising thereof; and means by which said brake strap is in opposition to the weight of the load released from the action thereof and said windlass mechanism is freed to pay out said cable.

5. A hoisting mechanism comprising a load-supporting cable; a load-raising windlass mechanism upon which said cable is wound to raise the load and from which said cable is paid out to lower the load; a brake mechanism which while set permits said windlass mechanism to be freely operated to wind up said cable and raise the load but which prevents said cable from being paid out to lower the load; a pulley over which said cable is rove; a lever from which said pulley is suspended; an arm which is mounted free to swing and which sets and releases said brake mechanism; a connecting device by which the weight of the load is transmitted from said lever to said arm to set said brake mechanism automatically; and means by which said arm is swung in opposition to the weight of the load to release said brake mechanism from the action thereof and permit said windlass mechanism to pay out said cable and lower the load.

6. A hoisting mechanism comprising a winding shaft; a brake-disk idly mounted thereon; a pawl carried by said shaft and arranged to engage said brake-disk; a brake-strap for said brake-disk; a load-supporting pulley; a swinging arm from which said brake-strap and pulley are hung; and means for throwing said arm in opposition to the weight of the load to release said brake-strap and permit said winding shaft to lower the load.

7. A hoisting mechanism comprising a winding shaft; a brake-disk idly mounted thereon; a pawl carried by said shaft and arranged to engage said brake-disk; a brake-strap for said brake-disk; a load-supporting pulley; an arm from which said brake-strap and pulley are hung; a shaft for controlling said arm; and an operating device shaped to engage and turn each of said shafts alternatively.

Signed at Jersey City, in the county of Hudson and State of New Jersey, this nineteenth day of November, A. D. 1913, in the presence of the two undersigned witnesses.

HENRY SHELDEN GERMOND, JR.
